UNITED STATES PATENT OFFICE.

WILLIAM A. SMITH, OF DENVER, COLORADO, ASSIGNOR TO THE DENVER ROCK DRILL MANUFACTURING COMPANY, OF DENVER, COLORADO, A CORPORATION OF DELAWARE.

DRILL-SHARPENING APPARATUS.

1,214,604.

Specification of Letters Patent. Patented Feb. 6, 1917.

Application filed February 23, 1916. Serial No. 80,916.

To all whom it may concern:

Be it known that I, WILLIAM A. SMITH, a citizen of the United States, residing at Denver, in the county of Denver and State of Colorado, have invented certain new and useful Improvements in Drill-Sharpening Apparatus, of which the following is a specification.

The present invention relates to drill sharpening apparatus, and more particularly to that type employing expansive motive fluid under pressure, such as air.

One of the primary objects is to provide exceedingly simple, and at the same time practicable apparatus of a novel character, which is compact, and which is relatively economical in the amount of air used.

An embodiment of the invention that is at present considered the preferable one, is illustrated in the accompanying drawings, wherein:

Figure 1 is a front view partially in elevation and partially in section of the apparatus. Fig. 2 is a rear view of the same. Fig. 3 is a side elevation partly in section. Fig. 4 is a detail cross sectional view on the line 4—4 of Fig. 1. Fig. 5 is a detail sectional view of the valve controlling the supply of motive fluid to the shaping hammer. Fig. 6 is a vertical sectional view through the valve controlling the supply of motive fluid to the work clamping means.

Similar reference numerals designate corresponding parts in all the figures of the drawings.

In the embodiment disclosed, a base 7 is employed which is hollow to provide an air chamber 8. On this base is located an anvil block 9, coacting with which is a head block 10 movable toward and from the same. These members are provided with the usual dies 11 and 12 for clamping the work in a manner well understood and they may also be provided with shaping dies 13 and 14.

The movable head block 10 is slidably upon a pair of spaced guide rods 15 extending upwardly from the base and passing through the anvil block 9, spacing sleeves 16 being located upon the guide rods and resting upon said anvil block. Located above the said guide rods is another fixed head block which includes a cylinder 17 having a depending neck 18 provided with outstanding ears 19 that are located upon the upper ends of the guide rods, resting upon

the sleeves 16 and being held in place by suitable nuts 20. The cylinder 17 has a lower integral head 21 provided with openings 22 and has an upper removable head 23 secured in place by suitable screw bolts 24, 60 said head having a central recess 25.

Operating in the cylinder 17 is a piston 26 of relatively great diameter, said piston having an upstanding central boss 27 that enters the recess 25. A piston rod 28, secured at its upper end to the piston 26, slidably passes through the neck 18, and is fixed to the sliding head 10. Formed on opposite sides of the neck 18, are smaller cylinders 29, the upper ends of which open into the large piston chamber of the cylinder and in these smaller cylinders 29 are located pistons 30 which bear against the under side of the piston 26 and oppose its downward movement.

Mounted on the base 7 is an outstanding bracket 31 supporting a well known type of reciprocating pneumatic hammer 32, which operates against a dolly 33 mounted in a bearing 34 and interposed between said hammer and the work clamping means.

Motive fluid supplied from any suitable source is conveyed to the apparatus through a pipe 35, one branch 36 of which leads to the cylinder 17, being connected thereto at 35 one side of the recess 25, as shown in Fig. 3. Another branch 37 has a hose connection 38 with the hammer 32, while a third branch 39 is in communication with both cylinders 29 below the pistons 30. A conduit 40, indicated in Fig. 4 connects the two cylinders 29. In the branch 36 is located a check valve 41 that permits the passage of fluid to the cylinder 17, but prevents its return. There is also located in this branch 36 a valve casting 42 shown more particularly in Fig. 6. The valve casting is provided with an upper inlet port 43 communicating with the branch 36, an outlet port 44 that leads to the cylinder 17, and an exhaust port 45 that is in communication with an exhaust pipe 46 leading into the chamber 8 of the hollow base 7. Slidably mounted in the valve casting 42 is a reciprocating valve 47 having spaced heads 48 and a depending stem 49 that extends below the casting. This stem is connected by a pitman 50 with the crank 51 of a rock shaft 52 journaled in the base and having a handle crank 53 at one end.

Located at the lower end of the branch 110

pipe 37 is a valve casing 54, a detail of which is illustrated in Fig. 5. This casing affords connection between the branch 37 and the hose 38, and located therein is a valve seat 55, with which coöperates an upwardly opening valve 56. A spring 57 bears against the valve to normally hold it in closed position, and a stem 58, depending from said valve, projects from the lower end 5 of the casing and rests upon one end of a lever 59 journaled, as shown at 60, upon the rear side of the base 7. The other end of this lever is forked, as shown at 61, and the rock shaft 52 is provided with a disk 62 10 having a pin 63 arranged to engage in the fork of the lever when the shaft is turned.

As already explained, the exhaust from the cylinder 17 passes into the chamber 8 in the hollow base 7, and a portion is allowed to escape through an opening 64 formed in the rear side of said base. A portion of this exhaust also escapes through an upstanding nozzle 65 mounted upon the base and directing the discharge against the 20 clamping and shaping dies 11 and 12.

Briefly described, the operation of the structure is as follows: If the handle 53 is turned in one direction sufficiently, the valve 47 is lowered to permit the port 44 to be in 30 communication with the exhaust port 45. Consequently, the air under the pistons 30 will raise the same, thereby elevating the piston 26 and the head block 10. This upward movement is cushioned, however, by 35 the boss 27 of the piston 26 entering the chamber 25, and thereby trapping and compressing the air therein, so that a blow of the piston against the cylinder head 23 is prevented. When the head block 10 is thus 40 elevated, the tool to be sharpened can be introduced between the head block and anvil, and upon a return movement of the actuating handle, the valve 47 will first be raised, so as to bring the supply port 43 of the valve 45 casing 42 into communication with the outlet port 44, thereupon air will enter the cylinder 17 above the power piston 26, depressing the same against the action of the pistons 30, and causing the bit to be clamped. 50 A further movement of the actuating handle 53 will cause the pin 63 to enter the forked end 61 of the lever 59, and raise the rear end of said lever, thereby opening the valve 56 and permitting the air to enter the hammer 32. The piston of this hammer will consequently be rapidly reciprocated and the blows thereof will be transmitted by the dolly against the end of the bit. When a reverse movement of the piston takes place, 60 the hammer 32 will be first stopped and afterward the supply of motive fluid to the cylinder 17 will first be cut off and then exhausted through the pipe 46 into the base of the machine, a portion of this exhaust 65 passing out through the opening 64, while

the remainder will be directed by the nozzle 65 against the holding and shaping dies, blowing off any scale that may accumulate thereon.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

Having thus fully described my invention, what I claim as new and desire to secure by Letters Patent, is:—

1. In a drill sharpener, the combination with a base having an anvil, of a movable head coacting with the anvil, a power cylinder supported above the anvil and head, a power piston operating in the cylinder and connected to the head, a return piston of smaller area than the power piston and located therebeneath, means for supplying motive fluid to the machine and conveying a portion to the power piston and a portion to the return piston and maintaining the same against the latter, means for controlling the fluid supplied to the power piston and exhausting it therefrom, and a fluid operated shaping hammer and dolly mounted on the base.

2. In a drill sharpener, the combination with a base having an anvil, of a movable head coacting with the anvil, a fixed head supported above the movable head and having an upper large piston chamber and a plurality of lower and smaller piston chambers communicating therewith, a power piston operating in the large piston chamber, return pistons in the smaller chamber operating against the power piston, means for supplying motive fluid to the machine and conveying a portion to the power piston chamber and a portion to the smaller piston chamber and maintaining the same in the latter, means for controlling the fluid supplied to the power piston chamber and exhausting it therefrom, and a fluid operated shaping hammer and dolly mounted on the base.

3. In a drill sharpener, the combination with a base having an anvil, of spaced guide rods fixed to the base and projecting above the anvil, a head block located between and slidably on the guide rods, a cylinder fixed to the guide rods above the head block, a piston in the cylinder having a depending connection with the head block and located between the spaced guide rods, and a fluid operated shaping hammer and dolly coacting with the anvil and head block.

4. In a drill sharpener, the combination with a base having an anvil, of spaced guide rods

- fixed to the base and projecting above the anvil, a head block slidably mounted on the guide rods, a cylinder having outstanding ears disposed below and in spaced relation thereto, said ears being secured to the guide rods, a piston in the cylinder having a depending connection with the head block, and a fluid operated shaping hammer and dolly coacting with the anvil and head block. 5
5. In a drill sharpener, the combination with a base having an anvil, of spaced upstanding guide rods fixed upon the base, a head block slidably mounted on the guide rods, a cylinder located above the guide rods and head block and having a depending neck and outstanding ears, the latter being mounted upon the guide rods, a piston operating in the cylinder and having a piston rod slidable in the neck and connected to the head block, and a fluid operated shaping hammer and dolly coacting with the anvil and head block. 10
6. In a drill sharpener, the combination with work clamping means, of work shaping means coacting therewith, a motor for the clamping means, a motor for the work shaping means, motive fluid supply means connected to the motors, valves respectively controlling the supply means, and an oscillatory actuating device having a crank connection with one valve, and a detachable connection with the other for successively actuating said valves. 15
7. In a drill sharpener, the combination with a base, of work clamping means, a work shaping means mounted thereon, a motor for the clamping means, a motor for the work shaping means, motive fluid supply means connected to the motors, valves respectively controlling the supply means, a rock shaft journaled on the base and having an operating crank, a crank connection between one end of the rock shaft and one of the valves, and a lever for operating the other valve, said rock shaft having an eccentric device that engages the lever for actuating it. 20
8. In a drill sharpener, the combination with work clamping means, of work shaping means coacting therewith, a motor for the clamping means, a motor for the work shaping means, a motive fluid supply conduit having branches leading to the two motors, a check valve in the branch leading to the clamping motor for preventing the re- 25
- turn of the fluid therefrom to the shaping motor when both are in operation, controlling valves for the branches, and actuating means for the valves whereby they may be successively operated. 30
9. In a drill sharpener, the combination with work clamping means, of work shaping means coacting therewith, a motor for the clamping means, a motor for the shaping means, valves respectively controlling the supply means, one of said valves having an operating element, and an actuating device connected to one valve for operating the same and having a detachable engagement with the operating element of the other valve 35
- 60
- 65
- 70
- 75
- 80
- 85
- 90
- 95
- 100
- turn of the fluid therefrom to the shaping motor when both are in operation, controlling valves for the branches, and actuating means for the valves whereby they may be successively operated. 30
10. In a drill sharpener, the combination with a hollow base, of a work clamp mounted thereon and including a movable member, a motor for actuating the movable member, including a cylinder and a piston operating therein, means for supplying motive fluid to the motor, and exhausting it therefrom, means for directing the exhaust into the hollow base, said base having an outlet port, and a nozzle connected to the base for directing a portion of the exhaust against the work clamping means. 35
11. In a drill sharpener, the combination with work clamping means, of a motor for actuating the same, means for supplying fluid to and exhausting it from the motor, a valve controlling both the supply and exhaust of said motor, work shaping means coacting with the clamping means, a motor therefor, means for supplying motive fluid to the last named motor, a valve controlling said supply only to the last named motor, a common actuating device, means moved by the actuating device for operating the first mentioned valve to alternately permit the motive fluid to be supplied to the motor of the work-clamping means and be exhausted therefrom, and means also moved by the actuating device to permit motive fluid to be supplied to the motor of the work shaping means only when motive fluid is supplied to the motor of the work clamping means. 40
